INVENTOR

ATTORNEY

UNITED STATES PATENT OFFICE.

HENRY P. GOERZ, OF MARION, SOUTH DAKOTA.

SPARK-COIL-TESTING DEVICE.

1,244,049.

Specification of Letters Patent. Patented Oct. 23, 1917.

Application filed April 7, 1916. Serial No. 89,658.

To all whom it may concern:

Be it known that I, HENRY P. GOERZ, a citizen of the United States, residing at Marion, in the county of Turner and State of South Dakota, have invented certain new and useful Improvements in Spark-Coil-Testing Devices, of which the following is a specification.

This invention relates to a spark coil testing device and more particularly to an apparatus which is designed to determine whether or not the coil box for an automobile is in proper working order; whether the secondary or primary coils of the coil box are defective, or whether the master vibrator contained within the coil box is properly adjusted or in working order.

The invention further aims to provide a device that may be kept in a garage or repair station where it may be used when it becomes necessary to test the adjustment of the vibrator of an automobile before tampering with the plugs, disturbing the carburetor, or adjusting the timer when determining a defect in the operation of the motor of an automobile.

The invention further aims to provide a device wherein advantage is taken of the spark which occurs in a gap in the wiring of a primary or secondary coil of a coil box, the color of the spark in a gap in the wiring of the primary coil being blue and the color of a spark in a gap in the wiring of the secondary coil being red. It is therefore one of the objects of the device to provide a construction whereby a spark will be created when the coil box is mounted upon the support with its terminals contacting with contacts provided for the same, the color of the spark determining where the defect, if any, lies in the coil box.

A further object of this invention is the provision of a spark coil testing device which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which:

Figure 1 is a perspective view of the device showing the wire therefor in diagram.

Fig. 2 is a transverse horizontal section on the line 2—2 of Fig. 1.

Fig. 3 is a diagrammatic view, the light lines indicating the wiring of the coil in a coil box and the heavy lines indicating the circuit of the apparatus constituting the invention.

The body of the device consists of a folding support which comprises the vertical supporting plate 1 which is provided with an aperture 2 at its upper end whereby it may be hung on a hook on the wall of the garage or repair station and a shelf 3 which is hingedly mounted to the lower edge of the supporting plate 1 by means of a hinge 4. Folding supporting arms 5 are provided with a joint 6 at their centers and have their ends pivotally mounted on the edges of the plate 1 and the shelf 3 by means of pivot pins or bolts 7 and from this construction it will be observed that the shelf 3 may be swung on the hinge 4 to a vertical position against the vertical plate 1 when the device is not in use.

The shelf 3 is provided with a central depression in which a contact plate 8 is mounted and secured in the bottom of the depression by a screw 9. The contact plate 8 is insulated from the shelf by means of a non-conducting washer and the screw 9 acts as a terminal for one end of the conducting wire 10 which leads from the batteries B. The vertical plate 1 is provided with a longitudinally extending depression or recess 11 and arranged in the recess is a pair of contacting plates 12 and 13 the contacting plate 13 being carried by the spring arm 14 which is secured to a plate 15 of insulating or non-conducting material by a fastening screw 16. The upper end of the arm 14, above the fastening screw 16 is bent as at 17 to provide a groove through which an adjustable conductor arm 18 is mounted having a handle 19 of non-conducting material. The contact plate 12 is mounted upon a spring arm 20 which is secured to the plate 15 at the opposite side to which the spring arm 14 is secured and is fastened by the fastening screw 21 and terminates in a sharp point 22. A terminal screw 23 is arranged on the spring arm 20 and receives the end of the conducting wire 24 which extends from the batteries B from the terminal opposite to the terminal to which the conducting wire 10 is fastened.

The vertical supporting plate 1 is provided at its upper end with an enlarged opening 25

- and it will be observed that the plate 15 is provided with a U-shaped cut-out portion which allows the sides of the plate 15 to be in position on opposite sides of the opening 25.
5. Fastened to the plate 15 in horizontal alignment with the conducting arm 18 is a small plate 26 from which a conducting finger 27 extends. The end of the conducting finger 27 and the end of the adjustable conducting arm 18 are bent at right angles to extend into the opening 25 and are again bent at right angles to have their points 27' and 18' projecting toward each other to provide a gap in the circuit when the coil box is in position on the device. The lower edge of the small plate 26 is provided with a point 28 which is small in formation to the point 22 of the end of the spring arm 20 and thereby provides a short gap in which a spark is made when the coil box is in position.
- By reference to Fig. 3 of the drawing it will be observed that the light lines represent the winding of the coil box and the contact plate 8 is in contact with the terminals 25 of both the secondary and the primary coils with the vibrator V arranged in the wiring of the primary coil. The contact plate 12 receives the opposite terminal of the primary coil and the contact plate 13 receives the opposite terminal of the secondary coil. When the circuit is thus completed the current will pass through the primary coil, and if the vibrator is in working order, a secondary current passes through the secondary coil and across the gaps between the points 18' and 27' and also between the points 28 and 22 where a spark will occur which will indicate that the coils and vibrator are in working condition. Should no spark occur, the adjustable conducting arm 18 will be thrust forwardly toward the point 27' until a spark occurs at the gap whereby the operator will be enabled to determine whether or not the vibrator and coils are defective and, if no spark occurs at all, the operator will know that a defect exists in the coil or vibrator.
- In reduction to practice I have found that the form of my invention illustrated in the drawings and referred to in the above description, as the preferred embodiment, is the most efficient and practicable, yet realizing that the conditions concurrent with the adoption of my device will necessarily vary, I desire to emphasize the fact that various minor changes in the details of construction, proportion and arrangements of parts may be resorted to, when required, without sacrificing any of the advantages of my invention, as defined in the appended claims.
- I claim:
1. In combination with a support, contact plates carried by the support and insulated therefrom, one of said contact plates arranged to contact with the terminals of both the primary and secondary coils of a spark coil and the other of said plates arranged to contact, one with the opposite terminal of the secondary coil and the other with the opposite terminal of the primary coil, means electrically connecting the last mentioned contact plates with each other, said electrical connection provided with a spark gap, and a source of current connecting the contact plate which receives both the secondary and the primary terminals with the contact plate which receives the opposite terminal of the primary coil.
  2. In combination with a vertical supporting plate and a horizontal shelf hingedly mounted on said plate, a contact plate mounted on said horizontal shelf and insulated therefrom, spring arms carried by said vertical supporting plate and insulated from said plate, contact plates carried by said spring arms, means forming a conductor of current from one spring arm to the other, said means also providing a gap in said conductor, and a source of current, said first mentioned contact plate and one of said second mentioned contact plates being connected with said source of current.
  3. In combination with a vertical supporting plate and a horizontal plate carried by the plate, a non-conductive plate mounted on said supporting plate, spring arms mounted on said non-conductive plate and having their free ends terminating in superposed relation in the vertical center line of said supporting plate, contact plates carried by the free ends of said spring arms, means for conducting the current from one spring arm to the other, said conducting means having a spark gap provided therein, one of said spring arms connected to a source of current, and a contact plate carried by said shelf and connected to said source of current.
  4. In combination with a vertical supporting plate and a horizontal shelf carried by said plate, a contact plate mounted in a recess in said shelf, spring arms mounted on said vertical supporting plate and having their free ends curved inwardly toward the center of said supporting plate and arranged in superposed relation to each other, contact plates carried by the free ends of said spring arms, an adjustable conducting arm carried by one of said spring arms, a conducting finger mounted adjacent the end of the other of said spring arms, the end of said conducting finger arranged in superposed relation to the end of said adjustable conducting arm, and a source of current connected to the said contact plate on said shelf and to the fixed end of one of said spring arms.
  5. In combination with a folding support, contact members mounted upon the said support and insulated therefrom, certain of the

- said contact plates being resiliently supported from the said support, a source of current, and means mounted upon the said support and associated with the resiliently mounted contact plates and connected to the said source of current for providing a spark gap, the said means including an adjustable member for adjusting the width of the said gap.
- 10 6. In combination with a supporting member, contact plates mounted on the said member and insulated therefrom, resilient arms supporting certain of the said plates, the said arms being insulated from the support, the said support having an opening
- therein and having the said resilient arms disposed on each side of the opening, means forming a conductor of current from one of the resilient arms to the other, the said means including an adjustable member extending 20 into the said opening and providing a gap adapted to be adjusted in width by the said member.
- In testimony whereof I affix my signature in presence of two witnesses.

HENRY P. GOERZ.
